UNITED STATES PATENT OFFICE

124,798

DESIGN FOR A SUCTION NOZZLE

Walter Crouch Reed, Vista, Calif.

Application June 5, 1940, Serial No. 92,838

Term of patent 7 years

To all whom it may concern:

Be it known that I, Walter Crouch Reed, a citizen of the United States, residing at Vista, in the county of San Diego and State of California, have invented a new, original, and ornamental Design for a Suction Nozzle, of which the following is a specification, reference being had to the accompanying drawing, forming part thereof.

Fig. 1 is a side elevation,
Fig. 2 is an end elevation, and
Fig. 3 is a bottom plan view of a suction nozzle showing my new design.

I claim:

The ornamental design for a suction nozzle, as shown.

WALTER Crouch REED.
